CLAIM

The ornamental design for a luminous signaling device for aircraft controls as shown and described.

DESCRIPTION

The patent or application file contains at least one drawing executed in color. Copies of this patent or patent application publication with color drawing(s) will be provided by the Office upon request and payment of the necessary fee.

1.1: Perspective of first color variation

1.2: Perspective of second color variation

1.3: Perspective of third color variation

1.4: Perspective of fourth color variation

The subject matter disclosed includes a process or period during which one color changes into another. This process or period forms no part of the claimed design.

The green color overlay depicts portions of the luminous signaling device for aircraft controls that form no part of the claimed design.

In the drawings, the broken lines depict environmental subject matter only and form no part of the claimed design.
